UNITED STATES PATENT OFFICE.

ROSCOE C. BACON, OF PORT NORRIS, NEW JERSEY.

MILK-BOTTLE HOLDER.

Application filed February 2, 1926. Serial No. 85,566.

This invention relates to new and useful improvements in bottle holders and has for its principal object the provision of such a holder adapted primarily for use in the handling of bottled milk and the like.

Another important object of the present invention is the provision of such a holder arranged to be secured to a house or like place and which will greatly aid and facilitate the 10 convenient and sanitary handling of bottled milk.

Another object of the present invention is the provision of such a holder having associated therewith new and novel means for indicating the amount of milk or cream that is 15 desired.

A further object of the invention is to provide a bottle holder of the nature stated which while extremely simple in its construction, is 20 nevertheless strong, sturdy, and durable, cheap to manufacture and well designed for the purposes for which it is intended.

With these and numerous other objects in view as will become more readily apparent 25 during the course of the following description, the invention resides in the novel construction, combination and arrangement of parts to be more fully hereinafter described, illustrated in the accompanying drawings 30 and particularly pointed out in the appended claim.

In the drawings forming a part of this application:

Figure 1 is a front view of a bottle holder 35 constructed in accordance with the present invention and showing in dotted lines a milk bottle associated therewith.

Figure 2 is a top plan view thereof.

Figure 3 is a sectional view on line 3—3 of 40 Figure 1.

Figure 4 is a sectional view on line 4—4 of 45 Figure 1.

Figure 5 is a front view of a somewhat modified form of the present invention and,

Figure 6 is a top plan view of Figure 5.

Reference now being had to the accompanying drawings and more particularly to Figures 1 to 4 inclusive, it will be noted that in carrying the present invention into practice, there is provided a substantially rectangular wire frame designated as a whole by the letter A and comprising in its construction the upper rectangular section 10 having the front and rear bars 11 and 12 and the 55 end bars 13. Positioned beneath the section 10 is a similar rectangular section 14, said

sections being connected together at each of their four corners by means of the vertical connecting bars 15.

Arranged within the upper rectangular section 10 are the three rings 16, 17 and 18 formed from heavy wire or the like, each of said rings being secured to the front and rear bars 11 and 12 by means of the diametrically opposed connecting portions 19 and 20, the two outer or end rings 16 and 18 being secured to the end bars 13 by means of the connecting portions 21 and 22 while the intermediate or middle ring 17 is secured to the outer rings 16 and 18 by means of the connecting portions 70 23 and 24.

Arranged within the lower rectangular section 14 directly beneath the upper rings 16, 17 and 18 are the wire rings 25, 26, and 27 and it will be noted by reference to Figure 2, that 75 these latter rings are somewhat smaller in diameter than the said rings 16, 17 and 18 so that when the bottles are inserted through the upper rings, they will rest upon the lower rings and thus be firmly held within the 80 holder.

Each of the rings 25, 26 and 27 are secured to the front and rear bars 28 and 29 of the section 14 by means of the connecting portions 85 30 and 31, while the outer or end rings 25 and 27 are secured to the end bars of the section 14 by means of the connecting portions 32 and 33 and the intermediate or middle ring 26 is secured to the outer rings 25 and 27 by means of the connecting portions 90 34 and 35.

Positioned at the front of the holder and secured to and extending between the corner bars 15, as clearly shown in Figure 1, is a substantially wide plate 36 having applied thereto a plurality of graduations or numbers 37 which, let us assume, indicate quarts of milk, cream or the like. The said plate 36 is provided adjacent its lower edge and beneath the numerals 37 with a longitudinally 100 extending slot 38 and held within the slot 38 and adapted for sliding movement along the plate 36 is the pointer 39.

Secured to the rear face of the said pointer 39 is a small substantially vertical rod 40, 105 said rod being bent at its opposite ends to provide the inwardly directed shoulders 41 and 42 which engage the opposite sides of the said slot 38. The shoulder 41 is provided with the laterally extending spring arm 43 110 which engages the rear surfaces of the said plate 36 for the purpose of retaining the

pointer in position while the shoulder 42 is provided with the laterally directed finger piece or handle 44 by means of which the pointer can be moved along the plate within the slot 38 for selective registration with the numerals 37.

The rear bar 12 of the upper rectangular section 10 is provided with the eyelets 45 through the medium of which the holder may 10 be attached to a house or any suitable support. In the application of the holder, it will be apparent from the above that after the same has been secured to a suitable support, that the bottles of milk or the like may 15 be inserted therein through the upper rings 16, 17 and 18 and that they will rest upon the somewhat smaller lower rings 25, 26 and 27. By simply grasping the handle or finger piece 44, the pointer 39 can be moved along 20 the plate 36 to register with any one of the numerals according to the number of quarts of milk or the like that may be desired. It will thus always be readily apparent to the party delivering the milk just what quantity 25 is desired and if more or less milk is wanted it is only necessary to move the pointer until it registers with the numeral indicating the proper amount.

Referring now more particularly to the 30 modification of the invention disclosed in Figures 5 and 6 of the drawings, there is shown a holder including the upper and lower rectangular sections 46 and 47 having front and rear and end bars similar to the sections 35 10 and 11 of the preferred form described hereinabove and being connected together in the same manner. In this form, there are carried by the end bars of the lower sections 47, the longitudinally extending parallel 40 bars 48 and 49 connected by the three pairs of transverse bars 50 and 51 upon which the bottles are adapted to rest. Secured to and extending between the front and rear bars of the upper section 46 are the transverse bars 45 52 and 53 and it will be noted that these bars

are positioned between the bars 51-50 whereby to provide somewhat larger openings in the upper section through which the bottles may be inserted.

Arranged on the front of the holder is a 50 plate 54 provided with a dial 53 and pivotally mounted in the center of said dial as at 54' are the pointers 55 and 56. The dial is provided with suitable graduations 57 divided into two sections to indicate respectively 55 quarts of milk and cream, this arrangement being clearly shown in Figure 5. The pointer 55 is adapted to indicate the amount of milk desired while the pointer 56 is adapted to indicate the quantity of cream desired and 60 in order to notify the party delivering the milk and cream as to the amount wanted, it is only necessary to move the said pointers about their pivot 54' until they register with the graduations indicating the proper amount. 65

While there has been described hereinabove and illustrated in the accompanying drawings two ways in which the present invention may be carried into practice, it will be understood that it is also susceptible of other 70 modifications and that any such modifications as properly fall within the scope of the appended claim may be resorted to without departing from or exceeding the spirit of the invention.

What is claimed as new is:-

An indicating device for milk bottle holders comprising a longitudinally extending graduated plate provided with a longitudinally extending slot, a rod slidable within said 80 slot, and a pointer carried by the said rod forwardly of said plate, said rod being provided at one end with a spring arm engaging the rear surface of the said plate for retaining the pointer in position while the other 85 end thereof is provided with a finger piece for facilitating the movement of the pointer along the said plate.

In testimony whereof I affix my signature.
ROSCOE C. BACON.
